SELECTING IMPULSE TRANSMITTER

Louis M. Potts, Evanston, Ill., assignor to Teletype Corporation, Chicago, Ill., a corporation of Delaware

Original application February 1, 1941, Serial No. 376,962. Divided and this application January 26, 1943, Serial No. 473,583

3 Claims. (Cl. 177—380)

The present invention relates to dialing apparatus for station selection systems and more particularly to this class of devices adaptable for use with start-stop communication systems.

This application is a division of U. S. application Serial No. 376,962 filed February 1, 1941.

A principal object of this invention consists in providing dialing mechanisms operable after the manner of automatic telephone switching apparatus but capable of reproducing pulsations that may be repeated through start-stop telegraphic apparatus of the code combination Baudot signal class and which will be effective to actuate station selecting equipment automatically in order to establish communication between calling and called subscribers' stations.

The use of station selection methods by means of manual dial equipment is equally desirable in printing telegraphy as it is in telephony. From a convenience and utility viewpoint it is proposed in accordance with the present improvement to so regulate standard dial apparatus by means of telegraphic regulating and periodicity safeguarding equipment as to make its use in conjunction with start-stop telegraphic systems equally practical. Toward this end a mechanical tie-up is effected between the dial apparatus and a start-stop regulated shaft of a keyboard transmitter whereby a station selecting dial of standard construction as known in telephony is utilized for generating a number of permutation code signals which are composed of but a single line change characteristic during the entirety of the code combination so as to reproduce a number of similar signal impulses which may thereafter be used to operate station selecting switches after the manner of standard telephone practice.

In carrying out this plan of operation, the permutation code signal for the letter M has been chosen because it is composed of three successive spacing impulses followed by four successive marking impulses simulating thereby an average length of dialing impulse for operating a station selection switch. Since start-stop apparatus is, in fact, employed for the purpose of generating these dial type signals with the dial equipment serving only as a means of initiating the start-stop equipment and determining the number of signals, there is in effect produced a step-by-step pattern of signal which is also in fact a start-stop signal and may therefore be received by start-stop apparatus such as tape transmitters, regenerative repeaters, etc., without impairment or need for auxiliary apparatus to insure against improper responses.

In attaining the above and other objects of the present invention, the principal embodiment described hereinafter utilizes a rotary dial mechanism operatively associated with a standard embodiment of start-stop permutation code transmitting keyboard. The dial may be operated manually by means of rotating a disc which is advanced by a finger movement until a predetermined mark or fingerhole thereof attains a stop. The disc is thereafter released and automatically responsive mechanism restores the disc to its normal position one step at a time. As each step is completed, and since a particular key lever of the transmitting keyboard is held depressed during such operation, there is obtained the transmission of a number of character M signals corresponding to the selecting index numeral which was dialed. Thus, if a destination selecting index is comprised of, say, six impulses the particular key lever and the transmitting apparatus are accordingly operated causing to be generated six permutation code signals of a particular letter, which accordingly constitute that number of station selecting impulses in succession. These impulses are received at a central station whereat they are effective to operate selecting switches to select an ultimate destination line over which start-stop messages may then be transmitted to a destination station.

The keyboard mechanism at each subscriber station is of standard arrangement and one of its character keys is depressed for a period of time commensurate with the degree of rotation of the calling dial at the same time the transmitter clutch is engaged for a corresponding number of cycles and as each character code is transmitted the dial is stepped back toward zero position. When the station calling dial reaches its zero position the transmitter is declutched, the key which had been held down is permitted to resume its normal condition, and the transmission of code signals is arrested. Accordingly, it will be understood that the number of call signals generated through the intermediation of the keyboard mechanism will correspond with the angular position to which the calling dial is rotated and from which the calling dial is returned to its zero position.

For a more comprehensive understanding of the present invention reference may be had to the accompanying drawings and to the detailed specification following hereinafter wherein like reference characters designate corresponding parts throughout and wherein,

55 Fig. 1 is a circuit diagram featuring the cen-

tral station equipment for selecting a destination station by apparatus embodying the present invention;

Fig. 2 is a fragmentary front elevation of a start-stop signalling system keyboard apparatus having applied thereto a station selecting dial according to the present invention;

Fig. 3 is a plan view of the apparatus illustrated in Fig. 2;

Fig. 4 is a side elevation of the apparatus illustrated in Fig. 2;

Fig. 5 is a detailed rear elevation of the rotary dial mechanism according to the present invention;

Fig. 6 is a timing diagram illustrating typical signal curves of start-stop permutation code signals; and

Fig. 7 is a perspective diagram of certain operating members which relate to the present invention shown separate from the telegraph key-board.

In the accompanying drawings the reference character 11 denotes generally a rotary dial type of station selecting switch. Essentially this unit is comprised of a disc 12 which is integrally associated with a stub shaft 13, Fig. 4, and is provided with the ten finger tip receiving apertures, one representing each numerical integer of the decimal series.

Shaft 13 is journaled in a bushing 14 which in turn is secured within a central opening of an enclosure case 15, the latter member, as best viewed in Figs. 3 and 4, being supported in an inclined position by means of a suitable supporting bracket 16. Within the case 15, shaft 13 carries integrally associated with it a ratchet wheel 17 having teeth which correspond in number and disposition to the finger engagement openings 57 of the finger wheel 12.

As with conventional telephone dials, the unit 11 is provided with a finger stop 18. The latter member is here formed of an arm extension originating from lever 19 that is rotatably supported upon said shaft 13. Stop 18 is rotatable through a slight angular distance as determined by the limiting pins 21 and 22 against the former of which said stop 18 is urged by a spring 23. Integral with lever 19 are two ears indicated 24 and 25, Fig. 5, the latter of which pivotally supports a pawl lever 26 as at pivot 27 and the former of which provides an anchor point for a spring 28 the other end of which is hooked as at 29 to the uppermost extremity of said pawl lever 26.

Pawl lever 26 is limited in its counterclockwise rotation about pivot 27 as urged by the afore-described spring 28 when its uppermost extremity encounters the stop lug 31 which in turn may also be integrally formed with the afore-described lever 19. Upon the rotation of lever 19 as when its finger stop extremity 18 is engaged during the final degrees of movement of finger wheel 12, pawl lever 26 will be moved bodily upward with pivot 27 advancing in a counterclockwise direction as viewed in Fig. 5 so that tooth 32 of pawl lever 26, the upper edge of which is inclined as indicated in Fig. 5, encounters the extremity 33 of a bell crank lever 35, Fig. 4, there will result the clockwise rotation of said pawl lever 26 about pivot 27 and in opposition to the return spring 28 as it accordingly yields to the extending portion 33 of bell crank lever 35.

Reiterating, the finger wheel 12 is operated by inserting a finger into one of the dial openings 57 which is opposite a numerical digit corresponding to an identifying character of the station

sought, and the finger wheel is rotated in a clockwise direction as viewed in Figs. 2 and 3, counterclockwise as viewed in Figs. 5 and 7. This movement causes disc 12 and ratchet wheel 17 to be concurrently displaced to a significant angular position as detent arm 34 rides over a corresponding number of teeth in ratchet wheel 17, indicative of the digit thus operated. The finger upon encountering stop piece 18 moves the latter member a distance corresponding to the space between stop pins 21 and 22 and the finger is withdrawn. Thereupon, lever 19, being under tension of spring 23 afore-described, endeavors to return to its original position as illustrated in the drawings and in so doing, pawl 26 is carried downwardly causing its tooth projection 32 to engage the extremity 33 of bell crank 35 and to rock the latter in a counterclockwise direction, Fig. 4, about its pivot 36 which motion is mildly resisted by the lever return spring 37. Pawl 26 continues to engage extremity 33 thereby holding lever 33-35 in its counterclockwise position (as viewed in Figs. 4 and 7) until arm 61, integral with ratchet 17, returns to cooperate with projection 62 to disengage pawl 26 from extremity 33, as will hereinafter appear.

The movement on the part of bell crank 35 is then immediately translated into a counterclockwise motion of the character M operating bail 38, Figs. 2, 4, and 7. As bail 38 is rocked in a counterclockwise direction, Fig. 2, its light acting return spring 39 becomes distended and its remote extremity 41 engages and depresses key lever 42 whereby there is generated, through the normal operation of the transmitter mechanism, a permutation code signal corresponding to the character M as this key lever is identified, Fig. 3.

A keyboard apparatus for transmitting signals of the type illustrated in curve A of Fig. 6 is more fully described and explained in U. S. Patent No. 1,595,472. For the purpose of explaining the application of the instant invention, it will suffice to state that upon the operation of any one of the key levers such as the particular key lever M indicated by the reference character 42, there is conditioned a set of five code bars each one of which supervises the performance of an associated goose-neck lever 43, Fig. 2, while also as a result of the operation of any one of said set of key levers there is effected a leftward movement on the part of common release bar 44, Fig. 4, the rotation of a trip lever 45, and ultimately the release of a declutching element 46. In consequence of the release motion on the part of lever 46, clutch elements 47 and 48 are brought together so that a single cycle of rotation is imparted to the set of transmitting cams generally indicated 49, Fig. 3, but thereafter the cam assembly 49 is arrested by trip lever 45 acting on clutch trip 46 notwithstanding that any operated key lever is continuously held down. It is accordingly necessary, under conventional practice, that a key lever depression be repeated a number of times in order to obtain a number of character transmission operations.

The principal performance of cam assembly 49 is to control successively the operation of a set of goose-necks 43 each of which in turn controls an individual pair of contacts of a set which are arranged in a parallel alignment. In addition to this utility, however, cam sleeve 49 in accordance with the instant invention performs a further purpose as will now be described. One of the cams of assembly 49 has been especially indicated 51. Against the periphery of this cam there

rides a follower roller 52 which, as best indicated in Fig. 2, is carried by one arm 53 of a bell crank member whose other arm 54 is pivotally connected to a pawl 55, the extremity of which is indicated 56 in Fig. 5.

In consequence of the afore-described arrangement, as cam 51 is rotated, there results a horizontal reciprocation of pawl 55 which, with its extremity 56 engages consecutively the teeth of ratchet wheel 17 causing the latter member to be rotated in a clockwise direction, as viewed in Figs. 5 and 7 (counterclockwise as viewed in Figs. 2 and 3) one step at a time. As each impulse or character M signal is transmitted during the rotation of cam assembly 49, so also by reason of the horizontal actuation of pawl 55 and through its engagement with ratchet wheel 17, there is effected a restoration of the finger wheel 12 one step at a time until the normal or zero position is resumed.

It will be recalled that finger wheel 12 when rotated in a clockwise direction as viewed in Figs. 2 and 3 is capable of a total movement corresponding to a certain number of composite digital movements each equal angularly to the distance between successive finger holes 57 of which there are ten in the conventional type of dial illustrated, and that the final degree of movement of any station selecting operation results, in addition to the rotation of finger wheel 12, in the movement of finger stop 18 through a limited distance as represented by the two stop pins 21 and 22. When the operator's finger is withdrawn, finger stop 18 being urged by the return spring 23 immediately seeks to resume the position as indicated in Fig. 5 whereat it rests against the stop pin 21. It is to be noted that during the operation of finger stop member 18 when it was rotated counterclockwise (Fig. 5) pawl 32 through its articulation at pivot 27 with an ear 25 which is integral with arm 19 is caused to be moved upwardly until its shoulder portion 32 overtakes the extremity 33 of bell crank lever 35. In passing over this extremity spring 28 yields sufficiently to permit said pawl 26 a slight clockwise movement about pivot 27 but after its shoulder 32 comes into the clear again pawl 26 resumes its relative position to arm 19 as indicated and shoulder 32 is placed above said extremity 33 of bell crank 35 awaiting the release of finger piece 18.

As a result of the influence of spring 23, when the operator's finger is removed, the entire assembly including arm 19 and pawl 26 are rotated clockwise, Fig. 5, as before stated. Shoulder of pawl 32 now positively engages the extremity 33 of bell crank lever 35 and causes the latter member to be rocked counterclockwise about its pivot 36 as viewed in Fig. 4. Presently stop arm 19 encounters the limit pin 21 and its movement is thereat arrested determining thereby the extent of rotation of bell crank 35 which rotation is opposed by the return spring 37. In consequence of the counterclockwise rotation (Fig. 4) of bell crank member 33—35 its farthest extremity which underlies one arm 64 of the bail lever 38 causes said arm to be raised against the tendency of a return spring 39, Fig. 2, effecting the depression of its key lever actuating extremity 41 as well as the rotation of its transverse ball portion 59. At the end of bail portion 59 uppermost in Fig. 3 there is integrally formed a trip arm 61 which carries the adjustable screw 62 for engaging the horizontally extending lug 63 as indicated also in Fig. 4.

In consequence of the operation of lever 38 there are effected two results. Firstly, key lever 42 is depressed, effectively reproducing the manual actuation for transmitting the alphabetical character M and secondly the clutch trip 46 is rotated which results in the release of spring actuated driven clutch member 48 so that it comes into engagement with clutch driving member 47.

In accordance with the conventional operation of keyboard telegraph transmitting apparatus such as the type illustrated in U. S. Patent 1,595,472, the continued depression of any key lever such as the key lever 42 may not result in the transmission of any more than one character signal. In other words, to effect the transmission of a number of character signals it is necessary to depress any key lever and to permit the same to resume its normal position a number of times corresponding to the number of signals to be transmitted. This safeguard is usually obtained by the provision of a trip release mechanism in connection with clutch 47—48. It is now proposed by providing the extension 61 of bail 38 and by withdrawing clutch trip 46 at the same time that key lever 42 is depressed to permit cam assembly 49 to rotate a number of revolutions corresponding to the number of character M signals which are desired.

As cam assembly 49 effects one revolution after another, its cam 51, Fig. 2, encounters follower roller 52 and rotates bell crank 53 clockwise in opposition to its return spring 66, and as these operations proceed successively the downwardly extending arm 54 of said bell crank causes the pawl 55 to be reciprocated to and fro. With each rightward movement of pawl 55, Fig. 7, leftward as viewed in Figs. 2 and 3, a succeeding tooth of ratchet wheel 17 is engaged and then pulled forward thereby causing the finger wheel 12 to be restored by clockwise rotation, Figs. 5 and 7.

When the normal or zero position of finger wheel 12 is ultimately attained arm 67 which is carried integrally with ratchet wheel 17 engages the projection 68 of pawl 26 causing the latter member to be rotated clockwise about its pivot 27 and in opposition to its spring 28. This movement withdraws shoulder 32 from the extremity 33 of bell crank lever 33—35 permitting the latter member under the influence of its restoration spring 37 to resume its normal position as indicated in Fig. 4. In consequence bail 38 is free to resume its normal position under the influence of spring 39 whereupon bail extremity 41 is withdrawn from key lever 42 and extremity 61 is withdrawn from the horizontal plate 63 of clutch trip 46.

In this manner there is effectively reproduced, by the use of a telephone station calling finger wheel 12, a system of transmitting a number of permutation code character M signals corresponding to the call number of impulses in a station selecting signal. As the station selecting signals emanate from the transmitter apparatus, generally indicated 68 in Fig. 1, they may, before arriving at the central office 69, be regenerated at a repeating station such as the one indicated 71. Typical repeating station apparatus is illustrated in U. S. Patent 2,104,273 and since the station selecting impulses are, in fact, a number of similar start-stop permutation code signals issued in series, they may be repeated over conventional start-stop apparatus such as illustrated in this disclosure without distortion.

75 Attention is directed to curves B and C of

Fig. 6, where there is shown respectively the minimum and maximum peak or tolerance characteristics of a dial signaling equipment such as is conventionally employed in telephony. Test observations have indicated that any dialing signal having a spacing characteristic smaller than that indicated in curve B or one larger than that indicated in curve C is likely to produce false responses in station selecting switches of this type. Accordingly, and since five unit permutation code signals of the type illustrated by the curve A are receivable in standard telegraph equipment, it has been found expedient to utilize a particular code combination which in accordance with convention has been assigned to the alphabetical character M which signal is indicated by the curve D to be utilized in the purpose of reproducing station selecting impulses of the type necessary in operating telephone switching equipment. The spacing characteristic of the code combination for letter M will, as may be noted by comparing curve D with curves B and C, constitute a spacing impulse greater in length than the minimum curve B and yet one which is less than the maximum impulse curve C. In composing the station selecting impulse of three code impulses contiguously arranged including the start impulse, it may be noted that a total length of spacing current, somewhat in excess of a median signal length, is thereby obtained. By observing curve D in comparison with curves B and C one may notice that a two code impulse signal, which corresponds according to custom with the code combination for the character V, is also usable as a station selecting switch operating impulse if preferred.

There will now be described briefly the circuit of Fig. 1 to illustrate the application of the present invention in the embodiment discussed above comprising a central station and a limited number of outlying stations. The reference character 68 designates a transmitting station which may be a unitary apparatus of the type illustrated in U. S. Patent 1,632,297 or of the type illustrated in U. S. Patent 2,177,077. This outlying station in addressing the central office 69 may transmit its signals over a line in which is located a repeater apparatus 71 which may be of the type shown in U. S. Patent 2,105,173 or of the type shown in U. S. Patent 2,104,273. Either of these classes of repeater apparatus partakes of the characteristic of signal regenerative repeater, that is, signals received from the outlying station 68 are duplicated and retransmitted from a battery local to the regenerating station 71 and in this manner distortion effects caused by conditions inherent in the line are eliminated by a well-known practice of reconstructing the original signals under the control of the transmitter 68 so that as they enter upon the succeeding line directed to the central station the true theoretical signal pattern is again produced.

At the central station the incoming line passes through the winding of a slow-to-release relay 72, thence over local line 74, contactor 73 and its normal make contact point 75, through the winding of relay 76, to ground. As a result of normal marking current on the line, relay 72 will become energized and remain in its attracted condition notwithstanding the signal interruptions due to the succession of line selecting impulses comprised of a series of character M code combination signals, but relay 76 will intermittently release and attract its armature 77 causing the latter element to be actuated from its front

contact point 78 toward its back contact point 79 and vice versa.

As a result of the energization of slow-to-release relay 72 there will be drawn up its armatures 81 and 82, the former receding from its back contact point 83 and engaging its front contact point 84, while the latter will be attracted to its sole front contact. As a result of the closure of armature 82 with its front contact a circuit will be established for operating the station selecting switch magnet 86, traceable from grounded front contact point 79 of relay 76 through armature 77, conductor 87, armature 82, its front contact of relay 72 which is normally energized, conductor 88 to the junction point 89, conductor 91, winding of magnet 86 to grounded battery at 92.

As a result of the operation of magnet 86 intermittently under the control of received signals the station selecting switch will be rotated in a step-by-step manner advancing the three wiper brushes 93, 94, and 95 so that they successively engage the contact points 96, 97, and 98, respectively, after the manner of station selecting switch operation more thoroughly explained in Kempster B. Miller's book of "American Telephone Practice," fourth edition, Chapter XXXIV, published 1905.

As operating magnet 86 is alternately energized and de-energized in response to the fluctuations of armature 77, the station selecting switch will advance its above recited wiper brushes until they attain a position corresponding to the number of station selecting impulses received, whereupon the station selecting switch will momentarily come to rest with one of the contact points 98 engaged by its wiper 95 for a period sufficiently long to cause the operation of slow-to-operate magnet 99. This is traceable over an obvious circuit from grounded battery 101, winding of slow-to-operate relay 99, line 102, wiper 95 and a particular one of its contact points 98, to the grounded bridging circuit 103. As a result of the operation of relay 99, its two armatures 104 and 105 will be attracted, the former coming into engagement with the contact point of contactor 73 and establishing a circuit for connecting the incoming line to the destination station, at the same time withdrawing contactor 73 from contact point 75 after the well-known manner of make before break switch operation.

Contactor 105 engaging contact point 106 completes a circuit for maintaining energized the station selecting operating magnet 86. This circuit is traceable from grounded battery 92, through the winding of rotary switch operating magnet 86, conductor 91 to the junction point 89, thence over conductor 88, front contact of armature 82, conductor 87, armature 77, (which is now released) contact point 78, contact point 106 and its armature 105 (which is now attracted) conductor 108, contact point 84 to grounded armature 81 (which is still attracted because normally current is flowing in the line). When contactor 73 is withdrawn from contact point 75 as above described there results the de-energization of relay 76. As a result of the attraction of armature 104 with the contact point of contactor 73 incoming line through the winding of relay 72 and local conductor 74 is continued over the contact point of contactor 73 and its associated armature 104, conductor 109, wiper 93 and one of its contact points corresponding to the selected station, thence out over one of the line conduc-

tors 111 to a particular destination station 112, 112A, etc.

After the communication with the destination station 112, 112A, etc., has been completed, the conductor may be broken at any point either between the central station and one of the destination stations or between the calling station 68 and the central station, and the apparatus will become restored to zero or normal condition in the following manner. Slow-to-release relay 72, being in circuit at all times, when the current is interrupted for a sufficient length of time to de-energize said relay its armatures 81 and 82 will be permitted to fall back removing ground at armature 81 from the circuit which had been holding energized the switch rotary magnet 86 as afore-described whereupon the armature 113 will be permitted to recede and come into engagement with its contact point 114. Thereupon ground will be introduced again to the circuit including winding of magnet 86 as follows: from grounded battery 92, through the winding of magnet 86, conductor 91, armature 113 and contact point 114, conductor 115 to the bridging circuit of the several contact points 97 and wiper 94, thence conductor 116, contact point 83 to grounded armature 81. As a result magnet 86 will become energized again attracting its armature 113 away from contact point 114 whereupon the circuit will again be broken for said magnet 86 which will again release its armature 113, etc., the operation continuing intermittently until wiper 94 resumes the normal position at which it engages the zero contact point 117 which does not connect with conductor 115. Since magnet 86 operates all of the wipers 83 to 95, inclusive, there will in this manner be effected the restoration of the switch to normal or zero condition in readiness for a succeeding station selection operation.

In illustrating the application of the present invention there has been chosen for arbitrary illustration the rotary line finder apparatus identified as Strowger step-by-step switches. To those acquainted with exchange office apparatus it will be evident that other forms of line finder systems, such as the panel or cross-bar selectors, are equally adaptable for use and that multiple digit selection may be obtained by the application of known circuit arrangements.

While the present invention has been explained and described with reference to but a single embodiment, it is to be understood nevertheless that numerous variations and modifications may be incorporated without substantial departure from the present invention. Accordingly, it is not intended to be limited to the specific details of the foregoing specification nor to the particulars of the accompanying drawings except as indicated in the hereunto appended claims.

What is claimed is:

1. In a telegraph transmission system, a keyboard apparatus comprising a plurality of individually actuatable keys, an impulse transmitting means including a rotatable shaft and a set of signal composing contact members controlled thereby, means responsive to the manipulation of any one of the keys to condition said set of contacts for transmission of code signals and to simultaneously release said rotatable shaft for a single cycle of control of said contacts,

means for causing a predetermined number of consecutive cycles of predetermined code signals comprising a dial manipulable from a normal position to different predetermined extents, a stop mechanism for said dial and movable therewith during the final portion of the movement of the dial to its final setting, means operable by the stop mechanism when so moved for simultaneously depressing one of said keys and for releasing said rotatable shaft for an indefinite number of cycles of control of the contacts, means controlled by the rotatable shaft for each of its control cycles for returning the dial step by step to its original position, and means controlled by the dial when it reaches its original position for disabling said means operable by the stop mechanism.

2. In a telegraph transmitter, key means, impulse transmitting means including a rotatable instrumentality and a set of contact controllers controlled thereby, means controlled by said key means for governing said contact controllers according to the manner of operation of said key means and to simultaneously initiate rotation of said instrumentality for a single cycle of control of said contact controllers, means for causing a predetermined number of consecutive cycles of predetermined code signals comprising a dial manipulable from a normal position to different predetermined extents, a stop mechanism for said dial and movable therewith during the final portion of the movement of the dial to its final setting, means operable by the stop mechanism when so moved for simultaneously operating said key means and for initiating rotation of said instrumentality for an indefinite number of cycles of control of said contact controllers, means controlled by the rotatable instrumentality for each of its control cycles for returning the dial step by step to its original position, and means controlled by the dial when it reaches its original position for disabling said means operable by the stop mechanism.

3. In a keyboard transmitter apparatus, a cyclically rotatable shaft, a plurality of key levers, a set of permutation bars controlled by said key levers, a corresponding set of code transmitting contacts, means on said shaft for operating said contacts, means responsive to the manipulation of any one of said keys to condition said contacts in accordance with the setting of said bars and to cause a single cyclic rotation of said shaft for a single cycle of control of said contacts, means for causing a predetermined number of consecutive cycles of rotation of said shaft comprising a dial manipulable from a normal position to different predetermined extents, a stop mechanism for said dial and movable therewith during the final portion of the movement of the dial to its final setting, means operable by the stop mechanism when so moved for simultaneously operating one of said key levers and for releasing said rotatable shaft for an indefinite number of cycles of control of said contacts, means controlled by the rotatable instrumentality for each of its control cycles for returning the dial step by step to its original position, and means controlled by the dial when it reaches its original position for disabling said means operable by the stop mechanism.

LOUIS M. POTTS.
